(57) CLAIM

The ornamental design for an automobile front grille, as shown and described.

DESCRIPTION

FIG. 1 is a front perspective view of an automobile front grille showing our new design;

FIG. 2 is a front view thereof;

FIG. 3 is a left side view thereof;

FIG. 4 is a right side view thereof; and,

FIG. 5 is a top view.

The broken lines in the drawings illustrate portions of the automobile front grille that form no part of the claimed design.
